UNITED STATES PATENT OFFICE.

EDWARD J. SARBACH, OF LAKEWOOD, OHIO.

BENDING-TOOL.

No. 830,104.

Specification of Letters Patent.

Patented Sept. 4, 1906.

Application filed May 15, 1906. Serial No. 317,000.

To all whom it may concern:

Be it known that I, EDWARD J. SARBACH, a citizen of the United States, residing at Lakewood, in the county of Cuyahoga and State of Ohio, have invented new and useful Improvements in Bending-Tools, of which the following is a specification.

This invention is a bending-tool, and more particularly a tool for straightening the edges of fruit-jar caps to make the same perfect fitting and insure a tight joint.

The object of the invention is to provide an improved tool of this kind which is adjustable to different-sized caps.

In the accompanying drawings, Figure 1 is an elevation of the invention. Fig. 2 is a bottom plan view. Fig. 3 is an elevation, partly in section, showing the application of the invention.

Referring specifically to the drawings, 5 denotes a clamp for engaging a jar-cap. The clamp comprises a plate 6, having at its ends downwardly-extending flanges 7, which are bent inwardly at their ends, as at 7^a, to engage the threads of the cap.

To the top of the plate 6 is pivoted a lever 8, which carries a plate 9, having a slot 10. One end of the plate is bent to extend downwardly, as at 11, on which is mounted a bending-roller 12. The plate 9 is fastened to the lever by a screw 13, extending through the lever and the slot 10 and provided with a thumb-nut 14.

In use the plate 6 is placed on top of the 35 jar-cap with the parts 8 engaging the threads

thereof, and the plate 9 is adjusted to bring the bending-roller into proper position on the flanges of the cap, as shown in Fig. 3. The lever is then swung around on its pivot with a downward pressure, which causes the roller 40 to travel over the flange and straighten out the same, so that a perfect fit is had. By making the plate 9 adjustable lengthwise on the lever the tool can be used on different-sized caps.

I claim—

1. A bending-tool comprising a clamp for engaging a jar-cap, a lever pivoted to the clamp, and a bending-roller carried by the lever and adjustable lengthwise thereon. 50

2. A bending-tool comprising a clamp for engaging a jar-cap, a lever pivoted to the clamp, a slotted plate carried by the lever, a screw extending through the lever and the slot in the plate, a clamping-nut for the 55 screw, and a bending-roller mounted on the plate.

3. A bending-tool comprising a clamp for engaging a jar-cap, a lever pivoted to the clamp, a plate carried by the lever and adjustable lengthwise thereon, and having a downward extension carrying a bending-roller. 60

In testimony whereof I have signed my name to this specification in the presence of 65 two subscribing witnesses.

EDWARD J. SARBACH.
